UNITED STATES PATENT OFFICE.

MARO V. PALMER, OF WILLIMANTIC, CONNECTICUT, ASSIGNOR TO THE AMERICAN THREAD COMPANY, OF JERSEY CITY, NEW JERSEY, AND NEW YORK, N. Y.

SLACK-THREAD CONTROLLER FOR SEWING-MACHINES.

SPECIFICATION forming part of Letters Patent No. 655,575, dated August 7, 1900.

Application filed October 1, 1894. Serial No. 524,614. (No model.)

To all whom it may concern:

Be it known that I, MARO V. PALMER, a citizen of the United States, and a resident of Willimantic, in the county of Windham and State of Connecticut, have invented certain new and useful Improvements in Thread-Unwinders, of which the following is a full, clear, and exact description, whereby any one skilled in the art can make and use the same.

10 My invention relates to improvements in that class of devices known as "thread-unwinders."

One object of my invention is to provide a device of this class to support a mass of thread wound around a spool, bobbin, spindle, or the like and to so construct the same that the tension of the thread as it is withdrawn or unwound from the bobbin or spool may be perfectly controlled; and a further object is

20 to provide means for varying the tension upon the thread and also to provide means for automatically stopping the rotary movement of the bobbin to prevent unwinding and release of tension in case of the stopping of the machine which is supplied with thread.

25 To this end my invention consists in the combination and arrangement, in a thread-unwinder, of the several parts as hereinafter described, and more particularly pointed out

30 in the claims.

Referring to the drawings, Figure 1 is a view in side elevation of a thread-unwinder embodying my invention, with parts cut away to show construction. Fig. 2 is a top or plan view of the same, with the bobbin removed. Fig. 3 is a detail view, in vertical central section, of a portion of the tension-arm, the bobbin-support, the tension-controlling device, and their supports. Fig. 4 is a detail view, in central vertical section, of the base and the parts supported thereon in a plane at right angles to the plane of Fig. 3, the tension-arm with respect to the base being in a position at right angles to that shown in Fig. 3 and with the brake disengaged from the bobbin-support. Fig. 5 is a detail view, in central vertical section, of a portion of the device, showing a modified form of my invention. Fig. 6 is a detail view,

partly in section, of the device in a plane at 50 right angles to the plane of view of Fig. 5, the tension-arm with respect to its supports being also in a plane at right angles to that shown in Fig. 5.

In the accompanying drawings the letter 55 *a* denotes a base, preferably circular in form, the letter *b* a standard secured to the base, and the letter *c* an arm pivoted to the standard and having at its outer end a socket to receive the upper end of a bobbin *d*, supporting a mass of thread *d'*, the lower end of the bobbin fitting a socket in the bobbin-support *e*, to which it may be secured in any ordinary manner. The base *a* is provided with a hub *a'*, having a recess, within which is located a bushing *f*. This bushing is secured against rotation in the hub *a'* by means of the set-screw *a''*, projecting through the hub and with its inner end binding upon the surface of the bushing. A sleeve *g* extends 60 downward through a central opening in the bushing *f*, the lower end of the sleeve resting upon the bottom wall of the socket in the hub *a'*, and a set-screw *f'* projects through the bushing *f*, with its inner end thrusting against 65 the outer surface of the sleeve *g*, this construction allowing the bushing to be rotated on the sleeve and clamped in any desired position for the purpose of controlling the tension of the spiral spring *h*, the lower end of 70 which is secured to the bushing *f*, the upper end of the spring being secured to a hub on the lower end of the tension-arm *i*.

The spring *h* is preferably removably secured to the bushing *f* and tension-arm *i*, as 75 shown, the spring surrounding the sleeve *g* and resting upon the upper surface of the bushing *f*, the upper end of the spring thrusting against the tension-arm *i*.

The tension-arm *i* is loosely mounted on 80 the sleeve *g*, a screw *i'* projecting through the tension-arm, the inner end of the screw lying in a cam-slot *g'* in the sleeve *g*. On the tension-arm *i* is mounted a brake-shoe *i''*, with its upper surface underlying the bobbin-support 85 *e* and adapted to thrust against the under surface of the bobbin-support as the arm is thrown upward by the engagement of the

screw i' with the cam-slot g' . It will be noted that the spring is so placed on the sleeve g that as the arm i is rotated to carry the brake-shoe away from the bobbin-support the spring is contracted and in its recoil assists in raising the tension-arm i . A retaining-screw k is inserted through the wall of the sleeve g , the inner end of the screw resting in a peripheral slot in the stem e' of the bobbin-support e . The screw is so placed in the sleeve as to allow the bobbin-support e a free rotation, but to prevent its accidental removal from the sleeve g in the application of the brake or otherwise, the effect of the action of the brake upon the bobbin depending to a certain degree upon the weight of the latter. In case the weight of the bobbin, however, should not be sufficient to stop its motion quick enough, the contact of the retaining-screw k with the lower surface of the peripheral slot in the stem e' of the bobbin-support e will provide additional means for stopping its rotation. In this instance the lower wall of the slot acts as a supplemental brake in the operation of the device.

In Figs. 5 and 6 a modified form of the invention is shown, a cam-ring l being secured on the sleeve g , and a cam-surface on the upper side of the tension-arm i being in engagement with the cam-surface on the ring l . In this latter construction the cam-ring serves the purpose of the cam-slot shown in the preceding figures of the drawings; but in this latter construction the cam-ring l is employed to force the tension-arm i downward as the latter is rotated, and the recoil of the spring h is relied upon to carry the tension-arm upward in a position to cause the brake-shoe to engage the under side of the bobbin-support.

In the operation of the device a strand m from the mass of thread d' projects through an opening in the upper end of the tension-arm i , the base a being secured in such position as to cause the thread under the pull of the machine which it is supplying to swing the tension-arm i to one side and cause the brake-shoe i^2 to be disengaged from the under side of the bobbin-support e . If for any reason a machine which is being supplied with thread suddenly stops, the arm i is immediately thrown to one side against the standard b , the brake-shoe i^2 being caused to engage the under surface of the bobbin-support e and act as a brake to immediately stop the rotation of the bobbin and preserve the tension on the strand m of thread.

I have shown and described herein the spring as aiding in carrying the tension-arm upward to cause the brake-shoe to engage the under side of the bobbin-support, and this form of the invention is preferred, although it is obvious that any form of spring may be used to cause the tension-arm to rotate on its support and a cam be used to cause the tension-arm to move forward or away from the bobbin-support and yet embody the invention.

I do not desire to claim, broadly, herein a

device wherein a brake-shoe is adapted to be carried into and out of contact with a revolute bobbin-support for the purpose of retarding its motion, one form of such device being shown in the prior patent to me, dated February 20, 1894, No. 515,160, the device described and claimed herein embodying simply one means of effecting the purpose of such prior patent to me.

I claim as my invention—

1. In combination in a thread-unwinder, a base, a revolute bobbin-support mounted on the base, a tension-arm rotatively supported on the base and having a brake-shoe underlying the bobbin-support, and a cam in engagement with the tension-arm to cause it to move vertically, all substantially as described. 70

2. In combination in a thread-unwinder, a base, a revolute bobbin-support supported on the base, a tension-arm rotatively supported on the base and having a brake-shoe underlying the bobbin-support, a cam in engagement with the tension-arm whereby the latter is forced toward or away from the bobbin-support, and a spiral spring underlying the tension-arm and tending normally to force the arm upward and to rotate it, all substantially as described. 85

3. In combination in a thread-unwinder, a base, a revolute bobbin-support supported on the base, a sleeve secured to the base and supporting the bobbin-support, a tension-arm rotatively mounted on the sleeve, a cam-slot located in the sleeve and in engagement with a projection from the tension-arm, and a spring surrounding the sleeve and underlying the tension-arm whereby the latter is normally rotated and moved upward, all substantially as described. 90

4. In combination in a thread-unwinder, a base, a bushing adapted to be secured to the base, a sleeve adjustably secured to the bushing, a cam-slot located in the sleeve, a tension-arm rotatively mounted on the sleeve and having a projection engaging the cam-slot, and a spiral spring secured to the bushing and to the tension-arm and tending normally to rotate the latter and also force it upward, all substantially as described. 100

5. In combination in a thread-unwinder, a base, a socket in the base, a bushing adjustably secured in the socket, a sleeve adjustably secured in the bushing, a cam-slot located in the sleeve, a tension-arm rotatively mounted on the sleeve and having a projection engaging the cam-slot, and a spiral spring secured to the bushing and to the tension-arm and tending normally to rotate the latter and also force it upward, all substantially as described. 110

6. In a thread-unwinding apparatus, in combination, a base, a revolute bobbin-support mounted on the base, a tension-arm rotatively supported and vertically movable on the base, a friction-brake operated thereby, and a cam connected with the tension-arm whereby horizontal oscillation of the tension- 130

arm gives vertical movement to the friction-brake and thereby, by the braking and unbraking action of the friction-brake, controls the rotation of the bobbin holder or support.

5 7. In a thread-unwinder, in combination, a base, a revoluble bobbin-support mounted on the base, and having a stem with a shoulder, a stop coöperating with said shoulder, a cam for moving the stem vertically whereby the 10 stop and shoulder are brought into engagement and a spring-actuated thread-guide connected with the cam.

8. In a thread-unwinder, in combination, a base, a swinging tension-arm underlying the 15 bobbin-support and adapted in its swinging movement to make contact with the under surface of the bobbin-support, a thread-guide borne on the tension-arm, a cam in operative connection with the tension-arm to cause it 20 to move vertically in its swinging movement,

a spring actuating the tension-arm in one direction, a stem for the bobbin-support, a peripheral groove located in the stem and a retaining-screw projecting into said groove.

9. A thread-unwinding apparatus comprising in combination a base, a revoluble bobbin holder or support mounted on the base, a tension-arm rotatively supported upon the base, a brake-shoe operated thereby, means arranged to be actuated by the tension-arm whereby 25 horizontal oscillation of the tension-arm gives vertical movement to the brake-shoe and whereby the braking and unbraking action of the brake-shoe controls the rotation of the bobbin holder or support, substantially as de- 30 35 scribed.

MARO V. PALMER.
